US0D1069392S

(12) United States Design Patent (10) Patent No.: US D1,069,392 S
(45) Date of Patent: * Apr. 8, 2025

(54) SHOE

(71) Applicant: NIKE, Inc., Beaverton, OR (US)

(72) Inventor: Kelly A. O'Connor, Beaverton, OR (US)

(73) Assignee: NIKE, Inc., Beaverton, OR (US)

() Term: 15 Years

(21) Appl. No.: 29/904,083

(22) Filed: Sep. 29, 2023

(51) LOC (15) Cl. 02-04

(52) U.S. Cl.

USPC D2/977; D2/947

(58) Field of Classification Search

CLAIM

The ornamental design for a shoe as shown and described.

DESCRIPTION

FIG. 1 is a front perspective view of a shoe showing my new design;

FIG. 2 is a side view thereof; and,

FIG. 3 is a rear perspective view thereof.

The broken lines immediately adjacent to the shaded area define the bounds of the claimed design and form no part thereof. The broken lines depicting the remainder of the shoe form no part of the claimed design.

1 Claim, 3 Drawing Sheets
